(57) **CLAIM**

The ornamental design for a feet bathtub, as shown and described.

DESCRIPTION

FIG. 1 is a perspective view of a feet bathtub showing my design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is an additional perspective view thereof, showing an application of the feet bathtub.

The broken lines shown in the drawings represent unclaimed portions of the design and form no part thereof.
